DIE HOLDER

Edward S. Cornell, Jr., Larchmont, N. Y., assignor,
by mesne assignments, to American Radiator &
Standard Sanitary Corporation, New York,
N. Y., a corporation of Delaware

Application January 22, 1936, Serial No. 60,171

18 Claims.

(Cl. 78—60)

My present invention relates to punching and forming machinery and more particularly to an improved resiliently mounted die holder.

In the cold working of metal and particularly in the cold working of non-ferrous metal such as copper or similar metal, wherein the material being worked upon is held in a die, and punches are used to cause a cold flow of the metal for the purpose of forming the same to the shape of the cavity in the die, there is a tendency for the punch or punches to adhere to the material being worked upon. Under such circumstances considerable force is required to free the punch or punches from the material being worked upon, and when once freed it has heretofore been impossible to control the force being applied to free the punch, with the result that the die holder, or the punches, or both, may be brought to a sudden stop against each other or against adjacent parts of the punch press in which the same are located, and such sudden stop has heretofore been the cause of serious damage to, or total destruction of, expensive punches, dies, or die holders, or even the punch press itself.

In my present invention I have sought to devise a die holder, and particularly a mounting therefor, which would obviate the objections to prior devices of this kind as above pointed out. To this end, I have devised a resiliently mounted die holder or analogous device which, while it may not decrease the tendency of the punch or punches to adhere or stick to the material being worked upon, will nevertheless take up the shocks incident to the sudden release of the punch or punches, and thereby obviate the liability of damage to, or spoilage of, either the dies, the die holder, punch or punches, or the punch press in which the same are mounted.

In carrying out my invention I preferably slidably mount the die holder in slideways forming part of the die holder mounting structure and arrange spring buffer elements between the slidably mounted die holder and the die holder housing forming a part of the crosshead to which the movable punch is connected. Also, and as a part of my present invention, I arrange wedges or similar tightening elements for the elements of the die, so as to resiliently mount the same on a fixed part of the die holder structure so that, as the punches move into position to perform their operation, the wedges or similar elements for maintaining the die elements in close relation to each other, are yieldingly forced into wedging position, and such resilient mounting takes up the shocks incident to the release of

the fixed punch from the material being worked upon.

My preferred die holder is therefore completely resiliently mounted and is movable by the movable punch into operative position by yielding pressure applied by the plunger of the punch press through the resilient mounting, such movement forcing the resiliently mounted die holder into position against a fixed part of the die holder and into working association with the stationary punch.

A feature of my invention therefore, is a resilient mounting for a die holder.

A feature of my invention is a die holder in which the die is moved under yielding pressure against a fixed stop during the operative movement of the punches or other tools.

A feature of my invention is a resiliently mounted die holder cooperating with a fixed and a movable punch, and in which the movable punch forces the die holder into association with the fixed punch under yielding pressure.

A feature of my invention is a resiliently mounted die holder in which the die elements held therein are yieldingly forced into close association with each other during the operative stroke of the punches associated therewith.

A feature of my invention is the provision of wedges for moving the die elements into operative relation to each other.

A feature of my invention is the provision of wedges for forcing and maintaining the die elements in operative relation to each other.

A feature of my invention is the provision of means for forcing the die elements into operative relation to each other with a force proportional to the force exerted on the material in the die elements while being worked upon.

In the accompanying drawings,

Fig. 1 is a front elevation of my improved die holder mounting, having associated therewith so much of the punch press as is necessary to illustrate the practical working thereof;

Fig. 2 is a side elevation of the structure shown in Fig. 1;

Fig. 3 is a section on the line 3—3 of Fig. 2, looking in the direction of the arrows shown in Fig. 2, and showing the resiliently mounted die holder in its uppermost or non-operative position, or an enlarged scale;

Fig. 4 is a view similar to Fig. 3, but showing the resiliently mounted die holder in its lowermost, or operated position;

Fig. 5 is a sectional detail view on the line 5—5 of Fig. 3, and

Fig. 6 is a section on the line 6—6 of Fig. 5.

Referring to the drawings, 10 designates a die bolster, which ordinarily forms an integral part of the die holder mounting, on the top face of which bolster 10 are secured, by bolts 11, a front slide 12 and a rear bracket 13. The front slide 12 and rear bracket 13 are spaced apart from each other by spacing members 14, such spacing members being tubular in form and through which, and through the front slide 12 and rear bracket 13, pass the threaded bolts 15, the protruding threaded ends of such bolts being furnished with nuts as shown, by means of which the front slide and rear bracket are securely held in position relative to each other. The front slide 12 and the rear bracket 13 are cut away to provide a space therebetween. Referring to Fig. 1, the faces of such cutaway portions are shown as forming vertical slide faces designated by the reference numeral 17. Such faces are also illustrated and designated in Fig. 3 and between such faces is slidably mounted the resiliently mounted die holder forming an element of my present invention.

25 The die holder is comprised essentially of a lower bridge member 18 and a top bridge member 19, secured together by means of a plurality of bolts 20, outer wedge blocks 21 being interposed between the indicated respective planar recessed portions of the bottom bridge 18 and the top bridge 19 to space the same apart. The assembly of the lower bridge, top bridge and outer wedges is movable vertically in the slideway formed by the front slide 12 and the rear bracket 35 13, the upper movement being limited in a manner to be hereinafter described, and the lower movement being limited by the engagement of the lower bridge 18 with the upper face of the die bolster 10.

40 The lower bridge 18 is provided with a central vertically arranged perforation 22, through which may pass the bottom punch holding screw 23, the bottom punch holding base 24 and the bottom punch 25. The bottom punch holding screw 23 seats in a depression in the upper face of the die bolster 10, and is secured in position by the bottom punch holding screw 26. In such arrangement the bottom punch 25 is stationary and immovable, being fixed to an integral part of the punch table (not shown).

45 The top bridge 19 is provided with a central vertically arranged perforation 27, through which may pass the cap 28 for the upper punch, and also the upper punch 29. The upper punch 29 is secured by the cap 28 to the upper punch holding screw 30, and this punch holding screw 30 is screwed into the punch stem 31. The punch stem 31 is screwed into the punch housing 32, which is of the nature of a cross-head, which, together with the punch stem 31, is secured to the ram of the punch press. The punch stem is provided with a main adjusting nut 33 and a main adjusting lock nut 34, these two nuts being employed to determine the position of the upper punch 29 with respect to the length of travel of the same through the perforation 27 in the top bridge 19.

50 On the top of the top bridge 19 on each side thereof are a plurality of spring studs 35 which are designed to hold in position the lower ends of coil springs 36. The upper ends of these coil springs 36 set in depressions or recesses in the punch housing 32. The punch housing 32 is also provided, adjacent to either 55 end thereof, with threaded perforations into

which screw the upper ends of stripper rods 37. These stripper rods 37 are provided with non-circular portions 38 arranged at various points along their lengths between the punch housing 32 and the top bridge 19, for the reception of a wrench with which to rotate and adjust the same in the threaded perforations in the punch housing 32.

60 The top bridge 19 and the lower bridge 18 are provided with aligned perforations, in alignment with the stripper rods 37, and in which aligned perforations and stripper rods 37 slidably pass, as clearly shown in Fig. 3. The lower portion of each perforation through the lower bridge 18 is formed with an enlarged counterbored portion 38, in which slides the head 39 of the stripper rods 37. Such counterbored portions 38 limit the upward movement of the stripper rods 37, and therewith pre-establish a relationship between the top bridge 19 and the punch housing 32. After the stripper rods 37 have been adjusted to determine the proper relationship of the punch housing 32 and top bridge 19 they are fixed in position by means of set screws 40, as clearly shown in Fig. 1.

65 Screwed to the lower face of the die bolster 10, and symmetrically arranged with respect to each other, and to the bottom punch holding screw 26, are spring studs 41. The spring studs 41 are arranged in pairs, as shown in the drawings and the lower ends of such studs are threaded as indicated by the reference numeral 42 to receive sets of adjusting and lock nuts 43 and 44 respectively. Each pair of studs 41 has associated therewith and freely slidably thereon, a washer plate 45 on which seat the lower end of coil springs 46. The washer plates 45 thus act as a fixed stop for the coil springs 46. Each pair of spring studs 41 also has slidably mounted thereon a spring pressure stud base 47, provided with seats for the reception and engagement of the upper ends of the coil springs 46.

70 Secured to each of the spring pressure stud bases 47 as by riveting, or in any other suitable manner, is the lower end of a spring pressure stud 48, the upper end of which is arranged for engagement with the bottom surface of the die bolster 10. The spring pressure studs 48 have formed integrally therewith and extending upwardly therefrom, and in axial alignment therewith a cylindrical member 49 less in diameter than the spring pressure stud 48. The die bolster 10 and the lower bridge 18 are provided with perforations in alignment with each other and in which perforations are slidably mounted the 75 stated cylindrical members 49.

75 When the spring pressure studs 48 are in engagement with the lower face of the die bolster 10, and the lower bridge 18 is in its uppermost position as shown for example in Fig. 3 the upper end of the members 49 lie below the surface of the stated planar recess of the upper face of the lower bridge 18.

80 The upper end of each of the cylindrical members 49 is drilled and tapped to receive the lower 85 cylindrical portion 50 and the threaded portion 51 of a wedge releasing rod 52. The wedge releasing rods 52 are provided with an enlarged cylindrical portion 53 at their upper ends, and such enlarged portions are slidably mounted in 90 perforations provided in the top bridge 19. The upper ends of the enlarged portions 53 are provided with non-circular portions 54 by means of which the wedge releasing rods 52 may be rotated to alter their position relative to the cylindrical 95

members 49 carried by the spring pressure studs 48. After adjustment, wedge releasing rods 52 may be maintained in adjusted position by the set screws 55 in the members 49.

5 The body portions of the wedge release rods 52 are arranged to slidably pass through vertical perforations in inner wedges 56, such wedges cooperating with the outer wedges 21, as clearly shown in Figs. 3 and 4. The inner wedges 56 10 are provided on their bottom ends with upwardly extending recesses in which are located coil springs 57. The lower ends of such coil springs 57 engage with the bottom of the recess in the upper face of the lower bridge 18. Such springs 15 urge the inner wedges 56 into engagement with the under side of the heads 53 of the stripper rods 52, when the die holder is at raised, i. e., its Fig. 3 position.

Referring to Fig. 6 it will be noted that a portion 20 of the lower surface of the inner wedges 56 is cut away, as indicated by the reference numeral 51a, and such cut away portion 51a provides a bevel 58 which cooperates with a corresponding bevel portion formed on a hardened steel plate 59 keyed into the recess in the lower bridge 18, and secured rigidly to such bridge by screws 60. This latter construction is provided for the purpose of accurately positioning the inner wedges 56 when the parts of the device are 25 in their uppermost position and the die members 61, 62—as later described—have been removed from their position between the top bridge 19 and the lower bridge 18.

The assembly of coil springs 46, spring pressure 30 studs 48, and the wedge release rods 52, forms a means for actuating the inner wedges 56 into operative position under a yielding pressure. Such pressure is commensurate with the strength of the springs 46, and the length of travel of the 35 die carrying members above described. Also such springs 46 act to release, without shock, the inner wedges 56 from their effective compression exerting position with respect to the die members, to be hereinafter referred to, and take a position 40 which will permit the removal and replacement 45 of the die members with respect to the carrying devices therefor.

The space between the inner wedges 56 is 50 amply wide to allow the insertion of cooperating die members 61 and 62. Such die members may have in their cooperating faces any form of cavity desired, the cavity to be fabricated in accordance with the shape it is desired to give to the material to be worked upon. Also in such die 55 members 61 and 62, and communicating with the cavity therein, are passages 63 and 64 communicating with the cavity aforesaid and in alignment with each other, and also in alignment with the top and bottom punches respectively.

On the front slide 12 is formed a bracket 65, the upper face 65a of which is substantially on the same level as the surface of the recess formed in the lower bridge 18 when such lower bridge 60 is in its uppermost position, or in the position shown in Figs. 1, 2 and 3. A portion—substantially one-half—of such upper face 65a is cut away, as indicated by the reference numeral 66 in Fig. 2, to provide a slideway for a slide member 67, the upper face 67a of which lies in the same horizontal plane as the upper face 65a of the bracket 65. The slide 67 has depending therefrom a lug 68 in which is secured by nut 69 one end of a shaft 70, and which shaft has its free 75 end slidably mounted in a suitable bearing pro-

vided on the front slide 12. On the shaft 70 is formed a rack 71, which engages with and is driven by a pinion 72 secured to a shaft 73 rotatably mounted on the front slide 12. Secured to the end of the shaft 73 is a hand wheel 74, by means of which the shaft 73, and therefore the pinion 72, may be rotated either clockwise or counter-clockwise.

Such rotary movement of the hand wheel 73 will impart to shaft 70 movement to the right or left, and therefore will impart a similar movement to the slide 67 parallel to the upper surface of the bracket 65.

Formed on the bracket 65 is a vertical member 75, the inner vertical face of which is always in substantial alignment with the left hand inner face of the inner wedge 56. Secured to the top face of the member 75 is a plate 76, having at its inner end a depending top runner 77. This top runner 77 is in alignment with a bottom 20 runner 78 which is inset into the upper face of the bracket 67. The upper and lower runners cooperate respectively with grooves 79 and 80 in the die member 61.

Secured to the slide 67 in an upwardly extending bracket 81, the inner face of which is parallel to the opposing face of the member 75, and when the slide 67 is in the position shown in Fig. 1, is in substantial alignment with the inner face of the righthand wedge 56, shown in Fig. 3. 30 Secured to the top of the bracket 81 is a plate 82 provided with a downwardly depending top runner 83 which is in alignment with a bottom runner 84 secured to the top face of the slide 67. The top and bottom runners 83 and 84 cooperate 35 respectively with top and bottom grooves 85 and 86 respectively in the die member 62. The slide 67 is held in position on the bracket 65 by gib 87. The die members 61 and 62, prior to the positioning thereof between the top bridge 19 and 40 the lower bridge 18, are respectively positioned on the bracket 65 and on the slide 67, and when thus positioned the hand wheel 74 is rotated to move the bracket 81 to the right, as shown in Fig. 1 thus separating the die members 61 and 62 45 from each other. While thus positioned the cavity formed in such die members collectively is separated into two parts, and therefore it is relatively easy for an operator to position a mass of material, such as the mass of material 88, in for 50 example, that portion of the cavity formed in the die member 61. The hand wheel 74 is again rotated, this time to move the bracket 81 toward the member 75 and bring the die member 62 into association with the die member 61. When thus 55 positioned the die members 61 and 62, as a unit, and guided by the stated top and bottom runners may be pushed off the bracket 65 and slide 67 into position between the top bridge 19 and the lower bridge 18, and between the inner wedges 60 56. When thus in position and with the mass of metal 88 in the cavity formed in such die members 61 and 62 the apparatus is in condition for operation.

Assuming the conditions stated above, that is, 65 that the parts of the device are in the position shown in Figs. 1, 2 and 3, with the die members 61 and 62 in cooperative relation with the top bridge and lower bridge, and with the inner wedges 56, and with the passages 63 and 64 in 70 such die members in alignment with the top punch 29 and the bottom punch 25 respectively, the following operations may take place.

The operator manipulates the lever (not shown) of the press to cause a downward move- 75

ment of the ram of the punch press (not shown), whereupon the punch housing 32 carrying the top punch 29 and the stripper rods 31 is moved downwardly from the position shown in Figs. 1, 2 and 3 toward the position shown in Fig. 4. The die holder assembly, comprising the top bridge 19, lower bridge 18, the outer and inner wedges and the die members 61 and 62 may or may not move downwardly at this time. However, as the punch housing 32 continues its downward movement the upper coil springs 36 will be compressed and a downward movement of the above assembly will take place. Such downward movement of the assembly will continue until the top of the lower punch 25 engages with the mass of material 88.

Also, and possibly at this time, the upper punch 29 will have moved into engagement with the mass of material 88. During such downward movement of the assembly the stripper rods 37 will move relative to the top bridge 19 and the lower bridge 18 and the heads 39 thereof will move into the passages 38a in the bolster 16 as shown in Fig. 4. Also, during this downward movement the lower end of the inner wedges 56 will move into engagement with the upper end of the cylindrical members 49 formed integral with and at the top of the spring pressure studs 48. This will result in a downward movement of the spring pressure studs 48, and a simultaneous downward movement of the spring pressure stud bases 41, with a consequent compression of the coil springs 46. Under these conditions there will be a resilient pressure exerted on the inner wedges 56 in an upward direction, and because of the construction of the adjacent faces of the inner wedges 56, and the outer wedges 21, there will be a lateral movement of each inner wedge 56 toward its associated die member, and a resultant compressive action on the die members 61 and 62 in a direction toward each other. The cavity formed in such two members will be completely closed preventing escape of the mass of material 88 when the same is acted upon by the upper and lower punches respectively.

As the downward movement of the punch housing 32 continues, the punches 29 and 25 will gradually assume the position relative to each other as shown in Fig. 4, and during such movement into such position the material of the mass of material 88 will be caused to flow into and fill the cavity in the die members 61 and 62 in which the material is located. The downward movement of the die holder assembly is terminated when the lower bridge 18 moves into engagement with the upper surface of the die bolster 16, and the downward movement of the punch 29 with respect to the die members 61 and 62 is terminated when the main adjusting lock nut 34 on the punch stem 31 engages with the upper surface of the top bridge 19.

It has been found that the punches 29 and 25 will frequently stick in the material 88 being worked upon, and that considerable force is necessary to withdraw such punches from the material. Also it has been found that more frequently the top punch 29 is the first of the punches to be released from such material, and therefore means must be used to afterwards release the lower punch 25 from such material. Heretofore when the upper punch 29 was released, force was being exerted on such punch 29, and upon the sudden release of such upper punch from the material 88 the entire upper punch carrying means would be brought to a

sudden stop against some portion of the punch press with consequent serious damage to the equipment.

In my present invention all such damage is obviated, as when the upper punch 29 is released from the material 88 there will be no sudden upward surge of the upper punch 29 and carrying parts therefor, as the springs 36 maintain the die holder assembly initially in engagement with the upper surface of the die bolster 16.

The punch housing 32, therefore, and all parts carried thereby, including the stripper rods 31 will move upwardly at a constant speed until the heads 39 of the stripper bolts 37 engage in the top of the counterboard portion 38 of the passages in the lower bridge 18, and the assembly above referred to will be forcibly and steadily moved upwardly. Such upward movement is assisted by the springs 46, which tend to move the spring pressure studs 48 and therefore the cylindrical members 49 attached thereto, upwardly from the position shown in Fig. 4 to the position shown in Fig. 3.

The upward movement of the assembly referred to will cause a freeing of the lower punch 25 from the material 88, and when this happens the upward movement of such assembly is accelerated because of the action of the coil springs 46. No shock will result because of such sudden movement of the stated assembly, as the shock to which the same might be subjected is absorbed by the still substantially compressed springs 36. Assuming the stated assembly to have been moved upward to approximately its Fig. 3 position, it is apparent that the enlarged cylindrical portion 53 on the wedge releasing rods 52 will come into sudden engagement with the upper surface of the inner wedges 56, with the result that such wedges will be moved downwardly into their Fig. 3 position, in which position removal of the die members 61, 62 from the die holder is permitted. Springs 57 cushion the impact of the heads 53 while maintaining the die members 61, 62 in suitable work-securing position.

The accompanying drawings and description illustrate and describe respectively one embodiment of my improved invention. While I have shown such embodiment somewhat in detail, it is to be understood that I may vary the size, shape and arrangement of parts comprising my improved device within relatively wide limits without departing from the spirit of the invention.

I claim:

1. In an improved mounting for a die holder, the combination of a die holder, mutually separable die members positioned therein, mutually displaceable wedges arranged to be disposed upon opposite sides of said mutually separable die members, and reciprocable means for jointly operating said die holder and said wedges to effect wedging relation of said wedges relative to said mutually separable die members in a movement of said reciprocable operating means and non-wedging relation of said wedges relative to said mutually separable die members in an opposite movement of said reciprocable operating means.

2. In an improved mounting for a die holder, the combination of a base, a die holder, mutually separable die members positioned in the die holder, mutually displaceable wedging means cooperating with the die members and the die holder, and arranged to be disposed upon opposite sides of said mutually separable die members, and reciprocable means resiliently carrying

said mutually displaceable wedging means and jointly operating said die holder and said mutually displaceable wedging means.

3. In an improved mounting for a die holder, the combination of a base, guide-ways thereon, a die holder mounted on the guide-ways, mutually separable die members positioned in the die holder, reciprocable means for resiliently supporting the die holder in position on the guide-ways, mutually displaceable wedging means co-operating with the die members and the die holder, and resilient means supported by said reciprocable die carrier supporting means for yieldingly moving the wedging means into operative relation with respect to said mutually separable die members in a movement of said reciprocable supporting means and into non-operative relation of said wedge means in respect to said mutually separable die members in an opposite movement of said reciprocable supporting means.

4. In an improved mounting for a die holder, the combination of a base, a die holder mounted for reciprocating movement toward and from the base, mutually separable die elements housed within the die holder, mutually displaceable wedging means carried by said die holder and associated with said mutually separable die members, and reciprocable means operative upon the movement of said die holder for moving said wedging means into wedging relation with respect to said mutually separable die elements upon movement of said die holder toward the base and for moving said wedging means into non-wedging relation with respect to said mutually separable die elements upon movement of the die holder from said base.

5. In an improved mounting for a die holder, the combination of a base, a die holder yieldingly mounted for reciprocating movement toward and from the base, die members housed within the die holder, wedging means in said die holder associated with the die members, and means mounted on the base engaging with said wedging means upon movement of the die holder toward the base to move said wedging means into wedging position with respect to said die members.

6. In an improved mounting for a die holder, the combination with a base, of guide-ways mounted thereon, a die holder mounted for reciprocating movement on the guide-ways toward and from the base, die members housed within the die holder, wedging means in said die holder associated with the die members, and means mounted in the base for moving said wedges into association with the die members whereby to move said die members into close association with each other.

7. In an improved mounting for a die holder, the combination with a base, of guide-ways mounted thereon, a die holder mounted for reciprocating movement on the guide-ways toward and from the base, a die comprising a plurality of separable members supported within said die holder, cooperating wedges mounted within the die holder and engaging the die members for moving the same into association with each other, and means carried by the base for moving said wedges into wedging position with respect to the die members during the movement of the die holder toward the base.

8. In an improved mounting for a die holder, the combination of a base, guide-ways mounted thereon, a die holder mounted for reciprocatory motion on the guide-ways toward and from the

base, die members mounted within the die holder and adapted to receive material being worked upon, wedging members mounted in the die holder for moving the die member into engagement with each other, and resiliently mounted means on the base engaging with the wedging means in the movement of the die holder toward the base for operating the wedging means.

9. In an improved mounting for a die holder, the combination of a base, guideways mounted thereon, a die holder mounted within said guideways for reciprocatory motion toward and from the base, a punch holder movable toward and away from said die holder, means secured to said punch holder and slidably mounted in the die holder for constraining said punch holder to move in a fixed path toward and away from said die holder, resilient means interposed between said die holder and said punch holder, a punch carried by said punch holder, and die members located within the die holder and adapted to receive material to be worked upon, said punch holder, upon movement toward said die holder, causing a yielding movement of the die holder and die members carried thereby toward the base as the said punch engages with the material within the die members.

10. In an improved mounting for a die holder, the combination of a base, a die holder yieldingly mounted for reciprocating movement toward and from the base, die members housed within the die holder, wedging means in said die holder associated with the die members, means mounted on the base engaging with said wedging means upon movement of the die holder toward the base to move said wedging means into wedging position with respect to said die members, and means for forcing the die members into close association with each other during the downward movement of the die holder.

11. In an improved mounting for a die holder, the combination with a base, a die holder yieldingly mounted for reciprocating movement toward and from the base, die members housed within the die holder, wedging means in said die holder associated with the die members, means mounted on the base engaging with said wedging means upon movement of the die holder toward the base to move said wedging means into wedging position with respect to said die members, and means for forcing the die members into association with each other with a force proportional to the force exerted by the punch on the material being worked upon.

12. In an improved mounting for a die holder, the combination of a base, guideways mounted thereon, a die holder mounted within said guideways for reciprocatory motion toward and from the base, a punch holder movable toward and away from said die holder, means secured to said punch holder and slidably mounted within the die holder for constraining said punch holder to move in a fixed path toward and from said die holder, resilient means interposed between said die holder and said punch holder, a punch carried by said punch holder, die members located within the die holder and adapted to receive material to be worked upon, the punch holder, upon movement toward the die holder, causing a yielding movement of the die holder and the die members carried thereby toward the base as the punch engages with the material within the die members, and means for yieldably forcing the die members into association with each other with a force proportional to the force exerted by

the punch on the material within the die members.

13. In an improved mounting for a die holder, the combination of a die holder having a die removably contained therein, guide means for said die holder, supporting means for said guide means, resilient means for mounting said die holder with respect to said guide supporting means, punch holder means operatively related to and on opposite sides of a die carried by said die holder, one of said punch holder means arranged for reciprocatory motion with respect to said die holder, means effective for joint operation of said punch holder means with respect to work placed in the die carried by said die holder and resilient means interposed between said reciprocatory punch holder means and said die holder.

14. In an improved mounting for a die holder, the combination of a die holder having a die removably contained therein, guide means for said die holder, supporting means for said guide means, resilient means for mounting said die holder with respect to said guide supporting means, punch holder means operatively related to and on opposite sides of a die mounted within said die holder, one of said punch holder means arranged for reciprocatory motion with respect to said die holder, means effective for joint operation of said punch holder means with respect to work placed in the said die, and resilient means interposed between said reciprocatory punch holder means and said die holder, each of said resilient means comprising a set of resilient elements disposed in mutually symmetrical relation to one or more punches or equivalent carried by said punch holder means.

15. In an improved mounting for a die holder, the combination of a die holder having a die removably contained therein, guide means for said die holder, supporting means for said guide means, resilient means for mounting said die holder within said guide means in a manner affording reciprocating movement, punch holder means operatively related to and on opposite sides of said die, one of said punch holder means arranged for reciprocatory motion with respect to said die holder, means effective for joint operation of said punch holder means with respect to

work placed in said die, stripper means associated with said die holder for limiting the movement of said die holder relative to said punch holder means, and resilient means interposed between said punch holder means and said die holder.

16. In an improved mounting for a die holder, the combination of a base having vertical guideways mounted thereon, die holder means slidably mounted for vertical movement within said guideways, said die holder having a die removably contained therein, punch holder means mounted for vertical reciprocatory movement with respect to said die holder means, resilient means interposed between said punch holder and said die holder, means for resiliently supporting said die holder above said base, and wedge means arranged to cooperate with said last-mentioned means during downward motion of said die holder to hold the die carried by said die holder in proper operative relationship to said punch holder means.

17. In an improved mounting for a die holder, the combination of a base having vertical guideways mounted thereon, a punch holder arranged for vertical reciprocatory movement with respect to said base and said guideways, a die holder slidably mounted in said guideways and arranged to dispose a die in operative alignment with respect to said punch holder, and resilient means acting in opposition on the upper and lower faces of said die holder for yieldably establishing a position of said die holder intermediate the said punch holder and said base.

18. In an improved mounting for a die holder, the combination with a base, of guideways mounted thereon, a die holder mounted for reciprocating movement within the guideways toward and from the base, a plurality of separable die members contained within the die holder, said plurality of members being in operative association to define suitable die means, wedging means in said die holder associated with said die members, and resilient means mounted in said base and operatively associated with said wedging means for urging said wedges into association with said die members to move said die members into proper operative relationship.
